RADIO REMOTE-CONTROL SYSTEM

Charles J. Marshall, Dayton, Ohio, assignor to
the United States of America as represented by
the Secretary of the Army

Application August 28, 1945, Serial No. 613,197

2 Claims. (Cl. 177—353)

(Granted under the act of March 3, 1883, as
amended April 30, 1928; 370 O. G. 757)

1

The invention described herein may be manufactured and used by or for the Government for governmental purposes, without the payment to me of any royalty thereon.

This invention relates to communication systems and more particularly to communication systems designed to control the operation of a device at a remote point.

It is often desirable to control the operation of several circuits at remote points from one single point. One example of this might be a method of bombing in which several bombing planes flying in a predetermined formation release their bombs simultaneously when the release button is operated in the lead plane. It is obvious that the remote control system for releasing the bombs must be light in weight since at least the receiving portion of the system must be carried in each of the bombing planes except the lead plane and the lead plane must carry the transmitting equipment for the system. The remote control system must also possess a high degree of reliability for if the system fails to drop the bombs at the proper time a second bombing run must be made over the target or the bombs may have to be jettisoned if a second bombing run is not practical. On the other hand, the system must possess a high degree of security, otherwise spurious signals from either friendly or enemy sources might cause the bombs to drop on friendly targets and thus cause great damage.

It is an object of the present invention, therefore, to provide a simple, novel system for controlling the operation of a plurality of devices at remote points from a single control point. A second object is to make the above remote control system as light, dependable and secure as possible.

A third object of this invention is to provide a remote control system that makes the maximum use of radio equipment presently employed in aircraft.

For a better understanding of the invention, together with other and further objects thereof, reference is had to the following description taken in connection with the accompanying drawing in which:

Fig. 1 is a block diagram of the invention;

Fig. 2 is a schematic wiring diagram of a portion of the receiving system; and

Fig. 3 is a schematic wiring diagram of a portion of the transmitting system.

Referring now more particularly to Fig. 1, there is shown a radio frequency transmitter 10 connected to an antenna 12. Transmitter 10 may

2

be of a type normally employed for voice communication, or it may be a specially designed transmitter, as it will be explained later. Assuming that it is a conventional communication transmitter, it should be operated on a channel or carrier frequency that is not in use by any other radio transmitters in the vicinity. A signal generator 14 and a signal generator 16 each produce an alternating voltage signal of a predetermined fixed frequency. The two signals from generators 14 and 16 respectively are mixed in an electronic mixer circuit 18 and are supplied to the input connection 20 of transmitter 10 through a switch 22. In the case of a conventional communication transmitter, input connection 20 might be the jack provided for connecting a microphone to the transmitter for voice communication. The apparatus just described constitutes the entire transmitter component of the remote control system.

The receiving component of the remote control system consists of a radio receiver 26 with its associated antenna 28. If transmitter 10 is a conventional communications transmitter, then receiver 26 may be the receiver normally employed to receive the signals from transmitter 10. The output lead 30 from receiver 26 is connected to each of three band-pass filters 32, 34 and 36. Signal output lead 30 may comprise the signal output jack provided for connecting a conventional headset to receiver 26. Band-pass filter 32 is designed to pass a narrow band of frequencies centered about the frequency of the signal produced by generator 14 while filter 36 is designed to pass a band of frequencies centered about the frequency of the signal produced by generator 16. Filter 34 is designed to pass a narrow band of frequencies intermediate the frequencies passed by filters 32 and 36. The output of filter 32 is connected through an amplifier 38 to the coil of a relay 40. Contacts 42 on relay 40 are normally open but are closed when the coil of relay 40 is energized. In a similar manner the output of filter 36 is connected through amplifier 44 to a relay 46. Contacts 48 on relay 46 are also normally open but are closed when the coil of relay 46 is energized. A third such connection is made from the output of filter 34 through amplifier 50 to the coil of a relay 52. In this case, however, the contacts 54 on relay 52 are normally closed but are opened when the coil of relay 52 is energized. Contacts 42, 48 and 54 are connected in series between terminals 56 and 58 of a "work circuit" 60. Work circuit 60 is the circuit, for example the bomb release mechanism, that is

controlled by the operation of the relay contacts. The operation of the system is thought to be evident from the above description of the apparatus, but an example is given to illustrate more clearly its operation. Assume that a 300-cycle signal is generated by generator 14 and a 3000-cycle signal is produced by generator 16. With switch 22 open, only the normal carrier frequency will be radiated by antenna 12. The output of receiver 26 is therefore only the small amount of noise usually found in the output of communication receivers. This noise is not of sufficient amplitude to cause an appreciable signal to be passed by any of the band-pass filters. With switch 22 closed, however, the signal transmitted from antenna 12 is modulated with both 300 and 3000 cycles and signals of these two frequencies will appear at output jack 30 of receiver 26. The 300-cycle-per-second signal passes through filter 32 and amplifier 38 and energizes the coil of relay 40. This causes contacts 42 to close. In a similar manner the 3000-cycle signal energizes the coil of relay 46 causing contacts 48 to close. No signal is present at the output jack 30 that will pass through filter 34; therefore, relay 52 remains deenergized and contacts 54 remain closed. The circuit between terminals 56 and 58 of circuit 60 is now complete, so circuit 60 will now perform the desired operation. Suppose now that switch 22 is open but that some random signal, for example voice or noise modulations having the same carrier frequency to which receiver 26 is tuned, is being picked up by antenna 28. The random signal in most instances will contain signals of 300 and 3000 cycles of sufficient amplitude to cause the energization of relays 40 and 46. This random signal will also contain signals that will be passed by filter 34 of sufficient amplitude to energize relay 52. It can be seen, therefore, that a random signal will close contacts 42 and 48, but will open contacts 54 and therefore will not cause circuit 60 to respond to a random signal.

It will be obvious to those familiar with radio theory that the signals produced by generators 14 and 16 may have any value whatsoever provided transmitter 10 and receiver 26 are designed to handle signals of the selected frequencies. It may be desirable to place a detector after amplifiers 38, 50 and 44 and replace relays 40, 52 and 46 with direct-current relays if the control frequencies produced by generators 14 and 16 are much above 5000 cycles. In other cases it may be desirable to eliminate amplifiers 38, 44 and 50 if the output of receiver 26 is of sufficient amplitude to operate relays 42, 48 and 54 directly.

Fig. 2 illustrates a further modification that may desirably be incorporated at times. Contacts 42, 48 and 54 and terminals 56 and 58 correspond to similarly numbered elements in Fig. 1. Switch 62 is added to provide means for manually operating circuit 60 at the remote point. It can be seen that closing switch 62 will have the same effect as closing contacts 42 and 48.

Fig. 3 illustrates a method whereby switch 22 at the control station is mechanically coupled to a switch 64 corresponding to switch 62, Fig. 2, so that a work circuit at the control point as well as one or more work circuits at remote points will be activated when switch 22 is closed.

While there has been described what is at present considered the preferred embodiment of

the invention, it will be obvious to those skilled in the art that various changes and modifications may be made therein without departing from the invention.

What is claimed is:

1. A remote control system including a transmitting component and a receiving component, said transmitting component comprising a first signal generator, a second signal generator, an electronic mixer for combining the signals produced by said first and second generators, a radio transmitter, and means including a switch for connecting said mixer to said radio transmitter, said receiving component comprising a receiver, first, second and third band-pass filters, said first and third filters being designed to pass signals having the same frequency as signals from said first and said second signal generators respectively, means for connecting the output of said receiver to each of said filters, first, second and third amplifiers for amplifying the signals passed by said first, second and third filters respectively, first, second and third relays responsive to the output of said first, second and third amplifiers respectively, means for connecting the contacts of said three relays in a series combination whereby a circuit is completed when said first and third relays only are energized and no circuit is completed when any other combination of relays is energized, and means for manually completing the circuit normally completed when said first and third relays are energized.

2. A remote control system comprising a transmitter having a first and a second signal generator, means for combining the outputs of said generators, a receiver having first, second, and third filters, said first and third filters being designed to pass signals having the same frequency as signals from said first and second signal generators respectively, said second filter being broadly tuned to the frequencies intermediate to the frequencies of said signal generators, first, second, and third relay means responsive to the outputs of said first, second, and third filters respectively, the contacts of said first and third relays being normally open and that of said second relay being normally closed, and means for connecting the contacts of said relay means in a series combination whereby a circuit is completed when only said first and third relay means are energized and no circuit is completed when any other combination of relay means is energized.

CHARLES J. MARSHALL.
